UNITED STATES PATENT OFFICE.

ERNEST S. KNEELAND, OF MALDEN, MASSACHUSETTS.

AUTOMATIC WEIGHING DEVICE.

1,109,293.

Specification of Letters Patent.

Patented Sept. 1, 1914.

Application filed November 21, 1913. Serial No. 802,267.

To all whom it may concern:

Be it known that I, ERNEST S. KNEELAND, a citizen of the United States, residing at Malden, in the county of Middlesex and State of Massachusetts, have invented a new and useful Automatic Weighing Device, of which the following is a specification.

The device forming the subject matter of this application is adapted to be employed for automatically weighing quantities of material which will flow readily.

The invention aims to provide novel means for controlling the closures of a receptacle in which the material is received, novel means being provided for directing the material first into one compartment of the receptacle and then into another compartment thereof.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawing:—Figure 1 shows the invention in side elevation; Fig. 2 is a section on the line 2—2 of Fig. 1; Fig. 3 is a transverse section; Fig. 4 is a detailed perspective of the latch.

In carrying out the invention there is provided a support 1 and as a preliminary statement it may be set forth that the support may be of any desired form and may be positioned as the exigencies of the proposed use of the structure may demand. In the present instance, the support 1 is shown as comprising a foot plate 2 supporting a standard 3. Surrounding the standard 3 and vertically adjustable thereon is a collar 4 held in place by a set screw 5, there being an arm 6 projecting from the collar and the arm terminating in a hoop 7. A collar 8 surrounds the standard 3 above the collar 4 and is fixed to the standard, the collar 8 being provided with a rearwardly extended arm 9 which is bifurcated to form guide fingers 10. Projecting from the collar 8 in

alignment with the arm 9 is an arm 11 terminating in an upright head 12. Arms 14 project from the collar 8 at an angle to the arms 11 and 9 and extend upwardly, the arms terminating in upright extensions 15. 60

Vertically adjustable upon the standard 3 above the collar 8 is a collar 16 held in place by a set screw 17, the collar 16 including a forwardly projecting arm 18 terminating in a supporting plate 19 as shown best in Fig. 65 2, the arm 18 and the plate 19 being provided with a band 20 or the like.

The invention includes a casing 21, the lower end of which is formed into an outlet funnel 22 fitting into the hoop 7. The head 70 12 of the arm 11 is secured to the casing 21. Located above the casing 21 is a hopper 23 including a laterally extended, inclined neck 24. The neck 24 is embraced by the band 20 and terminates in a spout 25 discharging 75 into the top of the casing 21. Guides 26 are mounted on the hopper 23 and mounted for reciprocation in the guides 26 is a gate 27 which controls the neck 24 of the hopper, the gate being actuated by means of the link 80 28 operated through the medium of a lever 29 which is fulcrumed on the hopper 23.

The invention further includes a loop-shaped scale beam 30 provided with trunnions 31 of the common knife edge form or otherwise constructed, the trunnions being pivotally received in the extensions 15 of the arm 14 so that the scale beam is fulcrumed intermediate its ends. Slidable upon one side portion of the scale beam 30 is a tare 90 weight 32 held in place by a set screw 33 or in any other suitable manner. The intermediate portion of the scale beam 30 is provided with a lug 34 to which a common weight supporting hanger 35 is pivoted. 95

Located within the casing 21 beneath the funnel 25 and between the side portions of the scale beam 30 is a receptacle 36 which is pivotally supported upon the scale beam as shown at 37. The receptacle 36 is divided 100 into two compartments by an upright partition 38.

Pivots supported in the receptacle 36 and located above the upper edge of the partition 38 is a movable baffle 39 having an arm 40. The arm 40 is adapted to be engaged by stops 41 on the receptacle 36. A lever 42 is fulcrumed intermediate its ends upon the receptacle 36, the fulcrum of the lever being indicated at 43. The upper end 110

of the lever 42 is loosely connected with the arm 40 by means of a pin or slot union and the like.

Pivoted at 44^a upon the receptacle 36 is a movable member or segment 44 provided in its upper edge with a notch 45 defining projections 46. The lower end of the lever 42 lies between the projections 46. Pivoted at 47 to the receptacle 36 is a latch 48 provided with a laterally projecting finger 49 received in a slot 50 formed in the segment 44 and adapted to coöperate with opposite edges of a tooth 51 which projects into the slot 50 from the body portion of the segment. Extended from the latch 48 in an opposite direction to the finger 49 is a finger-piece 52 which projects outwardly through the casing 21. Downward swinging movement of the free end of the latch 48 is limited by the engagement between the finger-piece 52 and the base or bottom of a slot 52^a in the casing 21, in which notch or slot the finger-piece 52 lies.

Closures 53 are pivoted as indicated at 54 to the receptacle 36 and control the egress of the weighed material from the compartments which are defined by the partition 38. Links 55 are pivoted to the closures 53 and are pivoted at their upper ends to the segment 44.

Let it be supposed that the gate 27 in the neck 24 of the hopper 23 is closed, that the movable baffle 39 is in the inclined position shown in Fig. 2 and that the lower end of the lever 42 is adjacent one of the projections 46 of the segment 44. Suppose that the finger 49 of the latch 48 is engaged with one side of the tooth 51 and that one of the closures 53 is in a position to cut off the outlet at one side of the receptacle 36—all of which details are clearly shown in Fig. 2.

Then the operation of the structure is as follows:—When the gate 27 is raised through the medium of the link 28 and the lever 29, the material in the hopper 23 will flow through the neck 24 and be delivered by the spout 25 against the inclined, movable baffle 39. The baffle 39 will direct the flowing material into one of the compartments in the receptacle 36, say the right hand receptacle in Fig. 2, until sufficient material has accumulated in this compartment to overcome the weight carried by the hanger 35. Then, the scale beam 30 will tilt upon its fulcrums 31—15 and the receptacle 36 will move downwardly. When the receptacle 36 moves downwardly, the finger 49 on the latch 48 will be disengaged from the tooth 51 of the segment 44. The segment 44 will be free to tilt on its pivotal support 44^a and the weight of the material, resting upon the right hand closure 53 will, through the medium of the right hand link 55 effect a swinging of the segment 44 to the right. By this operation, the left hand closure 53

will be moved to a closed position and the finger 49 on the latch 48 will interlock with the left hand side of the tooth 51. When the segment 44 is swung in the manner hereinbefore described, the left hand projection 46 on the segment will strike the lower end of the lever 42 and tilt the lever, motion being imparted to the baffle 39 through the medium of the arm 40, the baffle being swung over so as to direct the material flowing from the spout 25 into the left hand compartment of the receptacle 36.

From the foregoing it will be seen that successive charges of weighed material will be delivered automatically from the receptacle 36 into the discharge funnel 22.

It will be understood that should it be desired to dump either of the compartments of the receptacle 36 at any time manually, the latch 48 may be manipulated through the medium of the finger piece 52 to effect this result.

Having thus described the invention, what is claimed is:—

1. In a device of the class described, weighing means; a receptacle supported thereby and provided with compartments; a movable baffle carried by the receptacle and coöperating with the compartments individually; closures movable upon the receptacle and controlling the outflow from the compartments; a single movable member mounted on the receptacle; means for operatively connecting the said single movable member with the closures; means for operatively connecting the said single movable member with the baffle; a latch adapted to engage directly with the movable member; and means for supporting the latch; the receptacle being movable with the weighing means under an accumulated load to effect a disengagement of the movable member from the latch.

2. In a device of the class described, weighing means; a receptacle supported thereby; a movable baffle carried by the receptacle; a closure pivoted to the receptacle; a single movable member pivoted to the receptacle; a link connecting the said single movable member with the closure; a latch adapted to engage directly with the said single movable member; means for supporting the latch; and means for operatively connecting the said single movable member with the baffle.

3. In a device of the class described, weighing means; a receptacle supported thereby; and provided with compartments; a movable baffle; means for supporting the baffle for pivotal movement, the baffle being adapted to coöperate with the compartments; closures movable on the receptacle and controlling the outflow from the compartments; a single movable member mounted on the receptacle; means for op-

- eratively connecting the said single movable member with the closures; means for operatively connecting the said single movable member with the baffle; and means supported independently of the receptacle for controlling the movement of the movable member.
4. In a device of the class described, weighing means; a receptacle supported thereby and provided with compartments; a pivotally supported baffle coöperating with the compartments individually; a lever fulcrumed upon the receptacle and loosely connected with the baffle; a movable member pivotally supported upon the receptacle and provided with projections adapted to engage the lever; means for limiting the movement of the movable member; closures carried by the receptacle and controlling the compartments; and means for operatively connecting the closures with the movable member.
5. In a device of the class described, weighing means; a receptacle supported thereby and provided with compartments;
- 5 10 15 20 25
- a movable baffle carried by the receptacle and coöperating with the compartments individually; an arm projecting from the baffle; spaced stops upon the receptacle, between which stops the arm is adapted to move; a lever fulcrumed intermediate its ends upon the receptacle, one end of the lever being loosely connected with the arm; a movable member pivoted upon the receptacle and provided with spaced projections adapted to receive the other end of the lever, the movable member being provided with a tooth; a latch adapted to engage opposite sides of the tooth; means for supporting the latch; closures pivoted to the receptacle and controlling the compartments; and links pivoted to the closures and to the movable member.

In testimony that I claim the foregoing as my own, I have hereto affixed my signature in the presence of two witnesses.

ERNEST S. KNEELAND.
